UNITED STATES PATENT OFFICE.

THOMAS ALLATT, OF WESTFIELD, NEW JERSEY, ASSIGNOR, BY MESNE ASSIGNMENTS, TO MILLIE PATENT HOLDING CO. INC., OF NEW YORK, N. Y., A CORPORATION OF NEW YORK.

TEA CARTRIDGE.

Application filed August 31, 1922. Serial No. 585,413.

To all whom it may concern:

Be it known that I, THOMAS ALLATT, a citizen of Great Britain, and resident of Westfield, in the county of Union and State 5 of New Jersey, have invented certain new and useful Improvements in Tea Cartridges, of which the following is a specification.

The present invention relates to improvements in cartridges for percolating or extracting the flavor from tea-leaves or coffee. It pertains more particularly to cartridges made up of open-mesh textile fabric, such as cotton, each cartridge containing 10 a definite quantity of tea-leaves or coffee, sufficient for a single brewing.

Cartridges of this type are usually made in the form of a small bag or similar container, which is closed after the filling operation by suitable means. To the bag is usually fixed a string, to the free end of which is attached a handle, made, for instance, of cardboard. This string serves as the means for suspending the cartridge 20 from the receptacle, in which the extraction is to take place. In order to produce cartridges of this type, obviously quite a number of separate and distinct steps are necessary, to wit: First, a bag must be formed, second, the mouth of the bag must be closed, after the same has been previously filled with tea or coffee, third, a string of predetermined size must be cut and attached to the bag, this step being 25 preferably, done in the constructions heretofore in use, simultaneously with the bag closing operation, and, fourth, a cardboard handle or tag must be attached to the free end of the string, either before or after the 30 said string is attached to the bag.

The main object of the present invention is to provide a cartridge, which is so constructed that all of the steps above referred to are performed on a sewing machine 45 without interruption and, in addition thereto, the string is also produced by the sewing machine, thereby greatly simplifying the cartridge and its production.

With these and other objects in view, 50 which will more fully appear as the nature of the invention is better understood, the same consists in the combination, arrangement and construction of parts hereinafter described, pointed out in the appended 55 claims and illustrated in the accompanying

drawings, it being understood that many changes may be made in the size and proportion of the several parts and details of construction within the scope of the appended claims, without departing from the 60 spirit or sacrificing any of the advantages of the invention.

One of the many possible embodiments of the invention is illustrated in the accompanying drawings, in which:—

Figure 1 is an elevation of a tea-cartridge constructed in accordance with the present invention; and Fig. 2 is a section taken on line 2—2 of Fig. 1.

The cartridge is made up of a strip 10 of 70 open mesh textile fabric, such as cotton, said strip being folded at its transverse center line 11, a quantity of tea-leaves or coffee sufficient for a single brewing being interposed between the two plies 12 and 12' of the strip, 75 the respective free edges of the said two plies being then brought into abutment and united on a sewing machine by a line 13 of stitches. In this manner a cartridge is provided. In producing the line of stitches, a 80 sewing machine is used, whereby the thread of the stitch is carried over the edge of the two plies of the fabric, either by the needle or by some mechanism other than a needle. In this manner, the loose ends of the threads 85 are brought up against the edge of the fabric and held in concealed position by the thread of the stitches, or some special trimming means may be used for removing the said loose ends or thrums. A nicely finished cartridge is thus produced. After the cartridge has been stitched in the manner described, the line of stitches is continued, whereby a chain 14 is formed. This chain 90 may be of any suitable length, the stitches being then continued on a pasteboard tag 15, 95 as shown at 16, whereby the said tag is attached to the chain.

The cartridge may be of any suitable configuration, the fabric of which it is made being, preferably, sterilized before the tea-leaves or coffee are placed between the two plies, formed as above described.

In brewing tea or coffee with the improved device, the cartridge is taken hold 105 of by its handle 15 and lowered into the brewing receptacle, the free end of the chain 14 and handle being permitted to hang over the mouth of the receptacle, after which its cover is put into place. Into the receptacle 110

is poured a suitable quantity of boiling water, either before or after the insertion of the cartridge. The extraction of the essence thus takes place. The chain serves, as appears above, as the means of suspending the cartridge from the receptacle, such as a tea pot or a coffee pot, and also as the means whereby the cartridge may be handled.

From the foregoing it appears that all of 10 the steps of making the cartridge, with the exception of the filling operation, are performed by a sewing-machine in a continuous process, that is to say without interruption, the chain forming an integral part of the 15 means which unites the plies of the fabric, it serving at the same time to attach to the cartridge the handle or tag.

What I claim is:—

1. A device for extracting essence from tea- 20 leaves or coffee, comprising a strip of tex-

tile fabric having the material the essence of which is to be extracted placed thereon and then folded on its center line to form two plies contacting all around their free edges, a line of stitches extending close to 25 and in parallel relation to said free edges for uniting said two plies, the thread of said stitches being carried over the edge of the fabric, said stitches being continued beyond the fabric to form a chain which serves as a 30 suspending means for the device.

2. A device according to claim 1, comprising a tag on the outer end of said chain, the line of stitches being continued beyond said chain and passed through said tag. 35

Signed at New York, in the county of New York, and State of New York, this 13th day of April, A. D. 1922.

THOMAS ALLATT.
